UNITED STATES PATENT OFFICE.

CHARLES ANDREWS, OF SOUTH BEND, INDIANA, ASSIGNOR TO THE STUDE-
BAKER BROTHERS MANUFACTURING COMPANY, A CORPORATION OF
INDIANA.

SPRINKLER-HEAD.

SPECIFICATION forming part of Letters Patent No. 689,944, dated December 31, 1901.

Application filed February 16, 1900. Renewed May 1, 1901. Serial No. 58,361. (No model.)

To all whom it may concern:

Be it known that I, CHARLES ANDREWS, a citizen of the United States, and a resident of South Bend, St. Joseph county, State of Indiana, have invented certain new and useful Improvements in Sprinkler-Heads, of which the following is a specification.

This invention relates to sprinklers and such as are especially adapted for use in sprinkling roadways and flushing the gutters thereof.

The object of the invention is to provide a simple, convenient, and efficient sprinkler-head; and the invention consists of the features and combinations of features herein-after set forth, and more particularly pointed out in the claims.

In the drawings forming part of this specification, and in which like numerals designate corresponding parts, Figure 1 is a side elevation of a sprinkling-wagon with parts omitted and broken away, having attached thereto a sprinkler-head embodying the invention. Fig. 2 is a side elevation with the sprinkler-head detached, with the flushing-outlet turned upward. Fig. 3 is a sectional elevation on the line 3-3 of Fig. 2. Fig. 4 is a view similar to Fig. 3 and showing a modification. Fig. 5 is a detached side elevation of a modified form of sprinkler-head and partly broken away. Fig. 6 is a view similar to Fig. 5 and modified in one particular.

Referring now more particularly to the particular embodiments of the invention illustrated in the drawings, 1 is a casting, generally made of iron, having an inlet 2 at its inner end connected with the hose-pipe 3, which leads from the reservoir 4.

5 is a hanger to which the casting 1 is removably attached, the latter having slots 6, designed to receive bolts carried by the hanger 5.

The cylinder 7, which is bolted to the casting 1, is provided with suitable spray-outlets and also with a suitable gutter-flushing outlet. The spray-outlets may be in the form of slots or in the form of rows of perforations, as desired. They are preferably arranged circumferentially of the cylinder and in numerous lines and are graduated in size, their size increasing toward the upper side of the cylinder 7.

8 is a shield or cover adapted to slide circumferentially on the cylinder to cover and uncover the spray-outlets, its chief function being to close more or less (circumferentially 55 of the cylinder) of the spray-outlets, as when the sprinkling-wagon is passing a vehicle in the road. The shield 8 slides between the split ring 9 and a lip formed on the flange 10 of the cylinder. It is operated from the driver's 60 seat by a system of rods and levers 11, 12, 13, and 14.

The flushing-outlet 15 is arranged beyond the position of the spray-outlets and is designed for use in flushing gutters or other 65 parts of a roadway or in similar situations where a full stream is desired instead of a spray. The spray-outlets and the gutter-flushing outlet are both controlled by a piston, of which 16 is the cylindrical piston-head 70 having washers 17, and which piston-head is fixed on the piston-rod 18. The piston reciprocates within the cylinder. The end wall 19 of the cylinder is centrally apertured to afford one bearing for the piston-rod, the other bearing being formed on the bracket 20. The inner end of the rod may project into the recess 21. The piston-head need not fit the walls of the cylinder very tightly. A valve-seat is employed, which is located on the tank 80 side of the cylinder-outlets, and against this valve-seat the piston-head, acting as a valve, closes to shut off entirely the outflow of the water. This valve-seat is numbered 36, and, as shown in Figs. 3 and 4, it may be formed 85 at the inner end of the cylinder. It may of course be located at any convenient place on the inlet or tank side of the cylinder-outlets. By reason of the use of such a piston-valve and valve-seat it is not necessary to depend 90 on the circumferentially tight fit of the piston-head in the cylinder for the shutting off of the outflow of water, and hence the piston-head need not fit the walls of the cylinder very tightly, and the piston can be operated 95 with less power and with less wear upon the circumference of the piston-head and interior of the cylinder, and, moreover, the outflow of water can be shut off with less liability of leakage. I prefer to construct the outer part 100 of the cylinder with a slightly-enlarged interior 22, so that when the sprinkler is not in

use the piston-head may be drawn to that part of the cylinder and the circumferential packing thereby be preserved from deterioration, while the piston as a whole and its head and connected parts remain within the cover and protection of the cylinder and without withdrawing the piston from the cylinder. In the construction herein shown in Figs. 2, 3, and 4 this enlarged portion is also that portion of the cylinder in which the flushing-outlet 15 is placed. The entire cylinder is shown in Fig. 4 to be formed of one piece of metal. I prefer, however, to form that portion of the cylinder which constitutes or includes the gutter-flushing outlet 15 of a separate piece of metal from the rest of the cylinder, as shown in Fig. 3, arranging it for circumferential adjustment in order that the radial direction of the gutter-flushing outlet may be controlled. For this purpose in the particular construction shown in Fig. 3 the end part 22 of the cylinder is provided at its inner end with a split ring 24, having internal threads, so that it may be screwed onto the other part of the cylinder. A screw 25 passes through the projecting ends of the split ring 24 for the purpose of locking it firmly in any particular desired position. By loosening the split ring by means of screws 25 the part 22 of the cylinder may be rotated into the circumferential position desired or into the longitudinal position desired and there locked firmly and immovably again to the rest of the cylinder. In Fig. 1 the gutter-flushing outlet opens downward. In Fig. 2 it opens upward. It is of advantage to have the gutter-flushing outlet adjustable and of particular advantage to have it circumferentially adjustable, because in some cases it is desirable to throw the flushing-water directly downward, as into a gutter or in a particular part of the roadway, and in other cases it is desirable to throw the flushing-water to one side or the other at one angle or another or even directly upward. The gutter-flushing outlet may be of any size desired both longitudinally and circumferentially of the cylinder. In Fig. 5 it is shown at 28 as one hundred and eighty degrees long circumferentially and as somewhat narrow or contracted longitudinally of the cylinder. In Fig. 6 it is similarly shown at 29. In Figs. 1 to 4 it is shown at 15 as of the same circumferential length of one hundred and eighty degrees, but as somewhat broader or larger longitudinally of the cylinder. In Figs. 1 to 4 also the gutter-flushing outlet is shown as enlarged by the removal of the outer part of a sector of the end wall 19 of the cylinder; but this is not essential or important, as it merely reduces the weight and cost of the parts. Figs. 5 and 6 differ in that the end 26 of the cylinder in which the flushing-outlet is constituted in Fig. 5 is formed of a separate piece of metal from the rest of the cylinder, so as to afford adjustability to the flushing-outlet, whereas in Fig.

6 the end 27 is formed integral with the rest of the cylinder.

30 designates the outer end wall of the cylinder 37 in Fig. 5. 70

31 designates the outer end wall of the cylinder 38 in Fig. 6.

The piston is worked from the driver's seat through the system of rods and levers 32, 33, 34, and 35. 75

What I claim as new, and desire to secure by Letters Patent, is—

1. In a sprinkler-head the combination of a cylinder having an outer end wall, and having spray-outlets and a flushing-outlet in the side of the cylinder, a reciprocating piston controlling said outlets and working in said cylinder, an inner bearing for the piston on the inner side of both said outlets and an outer bearing for the piston formed in the end wall of the cylinder. 85

2. In a sprinkler-head the combination of a cylinder having an outer end wall, and having spray-outlets and a flushing-outlet in the side of the cylinder, a reciprocating piston controlling said outlets and working in said cylinder, an inner bearing for the piston on the inner side of both said outlets and an outer bearing for the piston formed in the end wall of the cylinder, the part forming the flushing-outlet being adjustable on the rest of the cylinder. 90

3. In a sprinkler-head the combination of a piston, a cylinder having an outer end wall, and having spray-outlets and a flushing-outlet, the latter outlet being formed in the side near the end wall of said cylinder, said end wall and the portion of the cylinder having the flushing-outlet being circumferentially adjustable so that the outflow through the flushing-outlet may be directed radially from the cylinder in various directions as desired. 100

4. In a sprinkler-head the combination of a piston, a cylinder having an outer end wall, and having spray-outlets and a flushing-outlet, the latter outlet being formed in the side near the end wall of said cylinder, said end wall and the portion of the cylinder having the flushing-outlet being circumferentially adjustable so that the outflow through the flushing-outlet may be directed radially from the cylinder in various directions as desired, the piston having a bearing in said adjustable end wall. 115

5. In a sprinkler-head the combination of a cylinder having an outer end wall and having spray-outlets and a flushing-outlet in the side of said cylinder, a reciprocating piston working in the cylinder and controlling said outlets, the outer part of said cylinder being of larger internal diameter than the piston-head. 120

6. In a sprinkler-head the combination of a cylinder having an outer end wall and having spray-outlets and a flushing-outlet in the side of said cylinder, a reciprocating piston working in the cylinder and controlling said

outlets, the outer part of said cylinder being of larger internal diameter than the piston-head and being circumferentially adjustable.

7. In a sprinkler-head the combination of a cylinder having an outer end wall, and having spray-outlets and a flushing-outlet in the side of the cylinder, a reciprocating piston controlling said outlets and working in said cylinder, an inner bearing for the piston on the inner side of both said outlets and an outer bearing for the piston formed in the end wall of the cylinder, and a valve-seat on the inner side of said outlets against which the piston-head closes to shut off the outflow of water.

8. In a sprinkler-head the combination of a cylinder having an outer end wall, and having spray-outlets and a flushing-outlet in the side of the cylinder, a reciprocating piston controlling said outlets and working in said cylinder, an inner bearing for the piston on the inner side of both said outlets and an outer bearing for the piston formed in the end wall of the cylinder, the part of said cylinder forming the flushing-outlet being adjustable, and a valve-seat on the inner side of said outlets against which the piston-head closes to shut off the outflow of water.

9. In a sprinkler-head the combination of a piston, a cylinder having an outer end wall, and having spray-outlets and a flushing-outlet, the latter outlet being formed in the side near the end wall of said cylinder, said end wall and the portion of the cylinder forming the flushing-outlet being circumferentially adjustable so that the outflow through the flushing-outlet may be directed radially from the cylinder in various directions as desired, and a valve-seat on the inner side of said outlets against which the piston-head closes to shut off the outflow of water.

10. In a sprinkler-head the combination of

a piston, a cylinder having an outer end wall, and having spray-outlets and a flushing-outlet, the latter outlet being formed in the side near the end wall of said cylinder, said end wall and the portion of the cylinder forming the flushing-outlet being circumferentially adjustable so that the outflow through the flushing-outlet may be directed radially from the cylinder in various directions as desired, the piston having a bearing in said adjustable end wall, and a valve-seat on the inner side of said outlets against which the piston-head closes to shut off the outflow of water.

11. In a sprinkler-head, the combination of a cylinder having an outer end wall and having spray-outlets and a flushing-outlet in the side of said cylinder, a reciprocating piston working in the cylinder and controlling said outlets, the outer part of said cylinder being of larger internal diameter than the piston-head, and a valve-seat on the inner side of said outlets against which the piston-head closes to shut off the outflow of water.

12. In a sprinkler-head the combination of a cylinder having an outer end wall and having spray-outlets and a flushing-outlet in the side of said cylinder, a reciprocating piston working in the cylinder and controlling said outlets, the outer part of said cylinder having the flushing-outlet being of larger internal diameter than the piston-head and being circumferentially adjustable, and a valve-seat on the inner side of said outlets against which the piston-head closes to shut off the outflow of water.

In testimony whereof I have signed my name to this specification in the presence of two subscribing witnesses.

CHARLES ANDREWS.
